UNITED STATES PATENT OFFICE

116,460

DESIGN FOR A CANDLE

Marcia C. Hamblet, New York, N. Y.

Application March 29, 1939, Serial No. 83,890

Term of patent 3½ years

To all whom it may concern:

Be it known that I, Marcia C. Hamblet, a citizen of the United States and a resident of the city of New York, in the county of Queens and State of New York, have invented a new, original, and ornamental Design for a Candle, of which the following is a specification, reference being had to the accompanying drawing, forming a part thereof.

The figure is a perspective view of a candle showing my new design.

The characteristic features of my design reside in a candle having its laterally disposed elements of greater width than the longitudinal elements, and the wicks at the top of the candle arranged in the specific manner shown.

I claim:

The ornamental design for a candle, substantially as shown and described.

MARCIA C. HAMBLET.
